UNITED STATES PATENT OFFICE.

TOM W. SAUL, OF SEATTLE, WASHINGTON.

DESIGN FOR A HAIRPIN.

57,995.

Specification for Design.

Patented May 24, 1921.

Application filed October 4, 1920. Serial No. 414,681. Term of patent 14 years.

To all whom it may concern:

Be it known that I, Tom W. SAUL, a citizen of the United States, residing at Seattle, in the county of King and State of Washington, have invented a certain new, original, and ornamental Design for a Hairpin, of which the following is a specification, reference being had to the accompanying drawing, forming part thereof.

Figure 1 is a front elevation and Fig. 2 is a side elevation of a hairpin showing my new design.

I claim;

The ornamental design for a hairpin, as shown.

Signed at Seattle, Washington, this 27th day of September, 1920.

TOM W. SAUL.
